LEWIS B. DOMAN, OF DE WITT, NEW YORK, ASSIGNOR TO THE AMPHION PIANO PLAYER COMPANY, OF SYRACUSE, NEW YORK, A CORPORATION OF NEW YORK.

TEMPO-GOVERNOR FOR SELF-PLAYING MUSICAL INSTRUMENTS.

1,160,054.

Specification of Letters Patent.

Patented Nov. 9, 1915.

Application filed March 20, 1914. Serial No. 825,951.

To all whom it may concern:

Be it known that I, LEWIS B. DOMAN, of De Witt, in the county of Onondaga, in the State of New York, have invented new and useful Improvements in Tempo-Governors for Self-Playing Musical Instruments, of which the following, taken in connection with the accompanying drawings, is a full, clear, and exact description.

10 This invention relates to certain improvements in tempo-regulating apparatus capable of being set to a predetermined position for establishing the normal time or tempo and of being adjusted from such position to effect greater or less variations above or below such normal time or tempo, and one of the primary objects is to provide a simple, practical and efficient means for automatically restoring the regulating means 20 to its normal position after having been voluntarily shifted therefrom.

Another object is to make the tempo-restoring means a part of the said device so that the same means may be employed for 25 setting the regulator to a predetermined position, adjusting it to and from such position for varying the tempo and automatically restoring it to such predetermined position when released.

30 A further object is to yieldingly hold the regulator in its predetermined position for a given tempo by means of a pneumatic gripping device controlled by suitable means within or upon the manual by which the 35 tempo-regulator is adjusted so that the operator may conveniently set, release or adjust the regulator with the same hand upon the manual.

Other objects and uses will be brought 40 out in the following description.

In the drawings Figure 1 is a perspective view of my improved tempo-regulating apparatus. Fig. 2 is an enlarged, longitudinal sectional view of the automatic restoring means including the compression spring and its tubular container forming parts of the setting and adjusting means for the regulator showing also the pneumatic gripping device with its gripping jaws in section. Fig. 3 is an enlarged longitudinal sectional view of the pneumatic gripping device shown in Fig. 1. Fig. 4 is an enlarged sectional view of the wind-chest containing the primary pneumatic valves for controlling the operation of the pneumatic gripping device. Fig. 5 is a longitudinal sectional view, partly broken away, of the tubular shaft and its operating manual or lever for setting or shifting the tempo-regulator and indicator, showing also a portion of the tube connecting 60 said shaft to the primary pneumatic for controlling the pneumatic gripping device. Fig. 6 is a sectional view similar to Fig. 4 of a modified form of valve for controlling the gripping pneumatic. Fig. 7 is a perspective view of a modified form of tempo-controlling lever having a normally closed atmosphere port. Fig. 8 is a side elevation, partly in section, of a portion of the same lever showing the normally closed port and 70 valve therefor.

In order that my invention may be clearly understood, I have shown a tempo-governing pneumatic —1— as mounted upon a combined wind-chest and valve-case —2— 75 in which is located a valve similar to that set forth in my Patents Nos. 1,097,706, May 26, 1914; Reissue Patent No. 13,764, July 7, 1914, and No. 1,118,189, Nov. 14, 1914, said valve being connected by a sectional rod 80 —3— to a crank arm —4— on a rock shaft —5—, the latter being journaled in suitable bearings —6— and provided with a hand lever or manual —7— by which it may be rocked to vary the position of the tempo-regulating valve. The pneumatic governor —1— and valve chest —2— are also similar to that set forth in my pending applications referred to and are connected by conduits —1'— and —2'— to a suitable wind-inducing device and pneumatic motor action (not shown), the sectional rods —3— being clamped together to operate in unison by means of a clamp —3'— whereby the valve may be properly adjusted to the throw of 95 the crank arm —4—. The rock shaft —5— is provided with an additional crank arm —8— connected by a sectional rod —9— to the lower end of an upright lever —10—, which, in turn, is fulcrumed or pivoted at 100 —11— to a suitable support —12— and has its upper end connected by a sectional rod —13— to a bar —14— carrying an indicator —15—, the latter being movable along a tempo scale —16— as the bar is shifted back 105 and forth by the rocking of the shaft —5— in reverse directions.

The means thus far described serves merely to shift the tempo-regulating valve and the indicator by which the position of 110

the valve may be determined, but I prefer to employ the same mechanism for operating a setting and restoring device whereby the valve and its indicator may be set to a predetermined position for playing a musical selection in a predetermined or normal tempo and at the same time, permitting those parts to be adjusted in opposite directions from their normal positions, said setting and restoring device consisting, in this instance of a relatively small tube 17 adapted to be moved endwise in the direction of movement of the indicator bar 14 but normally held against such endwise movement by and between a pair of gripping jaws 18 and 19 of a pneumatic gripping device 20, the ends of the tube being turned inwardly to form annular shoulders or abutments 21 for limiting the outward movement of a pair of sleeves or collars 22 which are slidable within the opposite ends of the tube and are normally held against the abutments by a compression spring or coil 23, the latter being also located within the tube 17 and has its opposite ends bearing against the inner faces of the sleeves or collars 22 as shown more clearly in Fig. 2.

The straight rod 24 is passed entirely through the center of the tube and also through the centers of the collars 22 and spring 23 so as to extend some distance beyond the opposite ends of the tube and is provided with relatively fixed collars 25 playing in the openings in the opposite ends of the tube and abut against the outer ends of the sleeves 22, one end of the rod being connected to the indicator bar 14, while the opposite end is movable in a suitable guide 26 shown more clearly in Fig. 1. The sections of each of the rods 9 and 13 are clamped in fixed relation by suitable clamps 9' and 13' which permit proper adjustment between the lever 10 and indicator bar and also between the lever and crank arm 8 so that the indicator bar may be accurately adjusted to the scale 16 to correspond with the position of the tempo-regulating valve in the valve case 2.

As previously stated, the coil spring 23 in the tube 17 is normally under compression and is sufficiently stiff to move the tube 17 endwise by the shifting of the indicator bar 14 through the medium of the rock shaft 5, links 9 and 13, and lever 10, while on the other hand, the pneumatic-gripping device 20 normally closes the jaws 18 and 19 with sufficient pressure or friction to hold the tube 17 against endwise movement when the indicator bar 14 is moved in either direction by the same operating means against the action of said spring in a manner presently described. The pneu-

matic gripping device 20 is normally open to atmosphere and, therefore, distended, the distention being aided by a V-shape spring 20' which operates to close the jaws 18 and 19 upon the tube 17 with increased pressure sufficient to hold it against endwise movement when the indicator bar 14 or tempo-controlling valves are shifted from their normal positions against the action of the spring 23, said pneumatic-gripping device being also adapted to be placed in communication with a suitable wind-inducing device, such as the usual pedal-operated pump or bellows (not shown but commonly employed in this class of instruments) and for this purpose I have shown a combined wind-chest and valve case 27 having a suction pipe 28 leading from a suitable wind-chest or wind-inducing device (not shown but in which a partial vacuum is normally maintained), the pipe 28 communicating with a suction chamber 29 in the valve case 27 as shown more clearly in Fig. 4. Within this valve case is located a primary pneumatic 30 communicating with a pipe 31 which leads from the valve case to the rear end of the rock shaft 5, said rock shaft being provided with an air passage 5' centrally therethrough from end to end and, therefore, communicates with the pipe 31 and also communicates with an air passage 7' extending upwardly to the upper end thereof so that the upper end of the passage 7' constitutes an air port normally open to atmosphere to allow the atmospheric air to pass through the hollow shaft 5 and tube 31 into the primary pneumatic 30 for distending the latter. The valve-case or wind-chest 27 is provided with a port 32 normally open to atmosphere and communicating with a branch port 33 to which is connected a pipe 34 leading into the pneumatic 20 so that the latter is also normally distended under atmospheric pressure.

A pair of puppet valves 35 and 36 are mounted respectively upon a valve stem 37 so as to seat respectively against the inner and outer ends of the port 32 which also communicates with the exhaust chamber 29, the valve stem 37 normally resting upon the diaphragm of the primary pneumatic 30 so as to normally close the valve 35 and open the valve 36, thereby normally cutting off communication between the exhaust chamber 29 and pneumatic gripping device 20 and at the same time opening communication between said pneumatic gripping device and atmosphere. It is now clear that when the atmosphere port 7' is open, the primary pneumatic 20 is distended to cut off communication between

the exhaust chamber —29— and pneumatic gripping device —20—, thus permitting said gripping device to grip and hold the tube —17— through the medium of its jaws —18— and —19— aided by the spring —21—, whereupon the lever —7— may rock in one direction or the other to rock the shaft —5— and thereby shift the positions of the tempo-regulating valve in the wind-chest —2— and move the indicator —15— along the scale —16— against the action of the coil spring —23—. That is, when the indicator-bar —14— is moved in one direction, as for example to the right, Fig. 2, the collar —25— at the left hand end of the tube will be drawn against the adjacent end of the collar —22—, thereby forcing the latter inwardly in the same direction against the action of the spring —23—, which is held against bodily movement, in the same direction by engagement of its opposite end with the collar —22— abutting against the shoulder —21— on the corresponding end of the tube —17—, but as soon as the pressure upon the lever —7— is released, the tempo-regulating valve and indicator will be restored to their normal positions by the retraction of the spring —23—. On the other hand, if the lever —7— is operated to shift the tempo-regulating valve in the case —2— and indicator bar —14— in the reverse direction so as to move said bar to the left, the collar —25— at the right hand end of the tube will be forced into said tube against the adjacent sleeve —22—, thereby moving said sleeve in the same direction against the action of the spring —23—, but as soon as the pressure upon the lever —7— is released, said spring will restore the shifted parts to their normal positions, thereby maintaining throughout the playing of a musical selection a more uniform tempo than would be possible if the tempo-regulating valve and index finger were not restored automatically. If it is desired to set the tempo-regulating valve and index finger in a different position, it is simply necessary to place the finger over the upper end of the atmosphere port —7— by which operation, atmospheric air is cut off from entering the primary pneumatic which is instantly placed into communication with the exhaust chamber —29— through a suitable bleed-hole as —38—, thereby causing the collapse of the primary pneumatic and allowing the valve —35— to open while the valve —36— closes, thus instantly placing the gripping pneumatic —20— in communication with the exhaust device to deflate said gripping pneumatic and thereby open its jaws —18— and —19— to release the tube —17—.

The release of the tube —17— by the collapse of the pneumatic —20— and opening of its jaws —18— and —19— is accomplished immediately upon the closing of the air port —7— in the lever —7— whereupon said lever may be rocked freely in either direction, thereby effecting a corresponding movement of the tempo-regulating valve in the case —2—, the indicator —15— and tube —17— until the valve and indicator are set to the desired position for a predetermined tempo after which the finger may be withdrawn from the governing port —7— to allow the restoration of the pneumatic —20— to its normal gripping position upon the tube —17— to hold the latter against endwise movement, thus holding the tempo-regulating valve and index finger in their normal positions and at the same time permitting them to be shifted from such position against the action of the spring —23— in the manner previously described with the assurance that the spring will automatically return those parts to such normal position when the lever —7— is released. In some instances, it may be desired to have the indicator and its actuating mechanism normally unlocked or free to remain in any of its adjusted positions, under which conditions, I may employ the valve structure shown in Fig. 6, in which a valve —36— is adapted to play between the atmosphere port —32— and an exhaust port —29—, but normally closing the atmosphere port and opening the exhaust port to cut off communication between the gripping pneumatic —20— and atmosphere and to establish communication between said pneumatic and the exhaust chamber —29—, whereby the gripping pneumatic will be normally deflated, thereby releasing its grip upon the tube —17— and allowing it, together with the indicator, to be voluntarily shifted in either direction, particularly when the primary pneumatic —30— is normally opened to atmosphere through the tubes —31—, hollow shaft —5— and apertured lever —7—.

In Figs. 7 and 8, I have shown a convenient form of tempo-controlling lever —40— adapted to be used in connection with either of the valve mechanisms shown in Figs. 1, 4 or 6, said lever being pivoted at —41— to a suitable support —A— to swing horizontally and is provided with an atmosphere port —42— connected by a conduit —43— to the flexible pipe —31—, but normally closed by a valve —44—, which forms a part of an extension or finger piece —45—, the latter being pivoted at —46— to the main body of the lever and is yieldingly held in its closed position by a spring —47— as shown more clearly in Figs. 7 and 8, thereby closing the port —42— and normally cutting off the communication between the primary pneumatic —30— and the atmosphere so that, when used in con-

nection with the valve mechanism shown in Figs. 1 and 4, the gripping device will be normally released from gripping engagement with the tube 17— thus leaving the tube indicator free to move in either direction. On the other hand, if the air port 42— is connected by its conduit 43— and flexible tube 31— to the primary pneumatic to the valve mechanism shown in Fig. 6, the valve 36'— will close the port 29'— and open the atmosphere port 32—, thereby normally establishing communication between the gripping device and atmosphere to hold said gripping device in its gripping position. The lever 40— is connected by a link 48— to a crank 7'— on a rock shaft 5— which may, in this instance, be solid and is provided with the usual crank arms 4— and 8— connected respectively by links 3— and 9— to the tempo-controlling valve and to the lever 10— for operating the indicator. It is now clear that the controlling levers 7— and 40— may be used in connection with either of the valve mechanisms shown in Fig. 4 or in Fig. 6 according to the necessity or desirability of having the slide indicator-operating member 17— locked or normally free. For example: When the lever 7— is used in connection with the valve mechanism shown in Fig. 4, the sliding member 17— will be normally locked to permit the springs therein to yieldingly hold the indicator in a predetermined position and, at the same time, permitting it to be shifted against the action of said springs, but, when the same controlling lever is used in connection with the valve mechanism shown in Fig. 6, the sliding member 7— is normally unlocked but may be voluntarily locked in any position by simply closing the port in the lever 7— by means of the finger. In a reverse manner, when the lever 40— is employed in connection with the valve mechanism shown in Fig. 4, the effect is the same as closing the port in the lever 7— and, therefore, normally releases the locking means to permit free movement of the sliding member 17— and indicator 50 and, at the same time, enables the operator to normally lock said sliding member and indicator by simply depressing the free end of the finger-piece 45— against the action of the spring 47— to open the port 42— to the atmosphere. When the lever 40— is used in connection with the valve mechanism shown in Fig. 6, the primary pneumatic 30— will be normally deflated thereby causing the valve 36'— to close the valve 29'— and open connection between the atmosphere port 32— and gripping pneumatic to cause the latter to normally lock the sliding member 17— and indicator in a predetermined position so that the effect is 60 substantially the same as in the use of the

lever 7— in connection with the valve mechanism 4—.

The operation of my invention will now be readily understood upon reference to the foregoing description and the accompanying drawing, and while I have shown and described specific forms of apparatus for carrying out in the invention, it is evident that other forms of devices may be employed without departing from the spirit of this invention, and, therefore, I do not limit myself to the precise construction shown and described.

What I claim is:

1. In a tempo-governing device, a tempo-indicator adjustable to different positions, and means for yieldingly holding said indicator in any position of adjustment, including a spring, an adjustable support therefor, and manually controlled pneumatic means for clamping the support in any of its adjusted positions, said spring being free to yield relatively to its support when the latter is clamped. 80
2. In a tempo-governing device, the combination with a tempo-governing valve adjustable to different positions, of means for yieldingly holding the valve in any of its adjusted positions including a spring, a sliding support therefor, and manually controlled pneumatic means for clamping the support in any position of adjustment, said spring being free to yield relatively to its support when the latter is held against movement. 90
3. In a tempo-governing device, the combination with a tempo-indicator adjustable to different positions, of means for yieldingly holding said indicator in any position of adjustment including a spring, a tubular container for the spring adjustable to different positions, and means operable at will for holding the container in any of its adjusted positions, said spring being free to yield relatively to its container. 100
4. In a tempo-governing device, the combination with a tempo-indicator shiftable to different positions, of means for yieldingly holding the indicator in any position of adjustment comprising a spring, connections between the spring and indicator, a tubular container for the spring adjustable endwise to different positions, and manually controlled pneumatic means for holding the tubular container in any position of adjustment, the portion of the spring connected to the indicator being free to yield relatively to the container. 110
5. A tempo-governing device having means for setting it to give a predetermined tempo, and separate means for yieldingly and adjustably holding it in such position, including a pneumatic gripping device operable at will. 125
6. A tempo-governing device having 130

means to vary the tempo at will, said means comprising a coil spring, movable means holding the spring under compression, connected plungers acting in reverse directions 5 on opposite ends of the spring, a pneumatic gripping device normally holding said movable means against movement, and additional pneumatic means operable at will for operating said gripping device to release it 10 from said movable means.

7. In a tempo-governing device, a tempo-indicator, a coil spring, connections between the indicator and opposite ends of the spring, a movable device for holding the 15 spring under compression, a pneumatic gripping device normally holding said movable device, and additional pneumatic means operable at will for releasing the gripping device from its holding position.

20 8. In a tempo-governing device, a tempo-indicator, a coil spring, connections between

the indicator and opposite ends of the spring to compress the latter in the direction of its axis as the indicator is moved in reverse directions, and means including a gripping 25 device operable at will for holding the spring against endwise movement in the direction of the axis of the coil.

9. In a tempo-regulating device for self-playing musical instruments, means adjustable at will to different positions to vary the tempo, and pneumatic means associated with the first named means for locking and releasing said first named means in and from any of its adjusted positions. 30 35

In witness whereof I have hereunto set my hand this 16th day of March, 1914.

LEWIS B. DOMAN.
